STAPLE

Max Vogel, Frankfort-on-the-Main, Germany,
assignor to The E. H. Hotchkiss Company,
Norwalk, Conn., a corporation of Connecticut

Original application November 14, 1932, Serial
No. 642,438. Divided and this application July
18, 1933, Serial No. 680,937

2 Claims. (Cl. 85—49)

The invention relates to the art of stapling and relates particularly to a wire staple of new formation which may be successfully used in an inexpensive construction of stapling machine such as disclosed in my application Serial Number 642,438 filed November 14th, 1932 and of which this present application is a division.

Heretofore, stapling machines have been constructed with guide shoulders or stops on the vertical walls of the guide channels through which the staple guide bars extend whereby to prevent the staples rising vertically off the guide bars. Such shoulders were necessary since the staples of commerce were all made with parallel shanks.

According to the present invention the staple is made up with its shanks inclined toward one another and with its back preferably arched and with the length of the arch corresponding at least to the distance between the shanks on the same being shifted into parallel relation.

The improved staple is shown in the accompanying drawing in which is also shown sufficient of a stapling machine in order that the advantages and manner of use of the improved staple may be fully illustrated.

In the drawing:

Fig. 1 is a side elevational view illustrating a desk type stapling machine;

Fig. 2 is a sectional view taken substantially along the line 2—2 of Fig. 1;

Fig. 3 is a sectional view taken substantially along the line 3—3 of Fig. 2;

Fig. 4 is a view similar to Fig. 3 but with the staple driving plunger depressed;

Fig. 5 is a front elevational view of the machine, the cover plate being omitted;

Fig. 6 is a somewhat similar view but with the staple driving blade also omitted;

Fig. 7 is a front view of the improved staple or of a strip of such staples; and

Fig. 8 is a side view of a strip of the staples of Fig. 7.

Referring in detail to the drawing, the stapling machine shown includes a frame 1 bent up of one piece and mounting a staple carrier or guide bar 2 articulated to the hinged block 3 of a base 4. The staple driving means is attached to the frame 1 by being mounted in channels 5 bent or formed by bending the front end of the machine. This driving means includes a supporting plate 6, a driving blade or driver 7, a plunger 10 carrying a press button 8, a plunger spring 9, and a cover plate 11. An anvil 13 is provided on the front portion of the base 4 and a spring 14 normally sup-

ports staple driving means in spaced relation to the anvil.

The staples 15 may be fed forwardly along the guide bar 2 by any suitable or known means as, for example, the follower 16 having ears 16a 5 mounting it on the removable guide rod 17. A spring 24 on such rod normally presses the follower forwardly against the staples so as to urge them toward the driving means and the staples may be loose or adhered in the form of a strip as 10 by any suitable cement.

According to the present invention the shanks 18 and 19 of the staples are inclined toward one another and the backs 20 of the staples are arched as best shown in Figs. 5 and 7. As will later appear, the staple's shanks are in each instance straightened or moved into parallel relation prior to the driving of the staple and it is preferred that the length of the arch correspond to the distance between the staple shanks when the 20 shanks are shifted into parallel relation.

To accommodate the staples 15 the carrier or guide bar 2 is under-cut or provided with side walls which incline outwardly and upwardly (see Figs. 5 and 6) whereby when the staples are 25 passed onto the guide bar from the outer end thereof, the staple shanks extend parallel with the side walls of the guide bar and the upper edges of the latter are farther apart than the lower edges thereof. With this arrangement the staples can- 30 not involuntarily rise with respect to the guide bar and there is no necessity for any particular arrangement of guide or guard means to hold the staples down on the guide bar. At its end toward the driving means the guide bar is closed as by 35 plate 12 the surface of which, looking toward the staple back, is flat.

From the foregoing it will be understood that the staples have their shanks inclined toward one another as shown in Fig. 7 when the staples are 40 positioned on the guide bar 2. Prior to the driving of the staples their shanks must be shifted into parallel relation or into positions at right angles to the back 20. To this end a rammer 21 is disposed in the rear of the driver 7 and secured 45 to the plunger rod 10 by a screw 22. Laterally, such rammer is guided in a slot in a gauge plate 23 located between the cover plate 11 and the supporting plate 6.

The staples 15 are fed one at a time into a race- 50 way through which the driver 7 is operable and the rammer 21 of course moves with said driver. As the driver moves downwardly on its working stroke the staple following the one in the raceway is under the rammer 21 and the latter strikes the 55

arched back of the staple (Figs. 4 and 6). This causes the shanks of the staple struck by the rammer to straighten or move into parallel relation and the staple so struck is then ready for driving and when the driver 7 returns to normal position the staple last struck by the rammer moves into the raceway beneath the driver.

When this occurs the next staple moves forward into position beneath the rammer and with its arched back against the rear lower portion of the driver (Fig. 5) and the driver maintains it in position. From this it will be clear that an arched staple cannot move into the raceway and since the staples are re-shaped by the rammer 21 only one at a time and as necessity arises it will be clear that but one staple at a time enters the raceway and that clogging of the staples in the raceway is avoided.

It will now be clear that with the construction of staple here disclosed a machine for using such staples may be of extremely simple construction since such a machine need not include any guide preventing involuntary rising of the staples relative to the guide bar and since the machine does not include any special means or any extra part

serving to prevent a second staple entering the raceway when one staple is already in the raceway. Further, it is to be understood that the staple is not limited to use in a desk type stapling machine but may be used in other stapling devices such as stapling pliers, stapling hammers, etc.

Having thus set forth the nature of my invention, what I claim is:

1. A wire staple for stapling devices, said staple including a connecting back and shanks inclining toward one another, said connecting back being upwardly arched, said arched back adapted to be straightened before application of the staple, and said shanks adapted to assume a parallel relationship when said arch is straightened. 15

2. A staple for stapling devices comprising a connecting back portion and side shanks normally inclined toward each other extending from the same side of the back, said back being arched in a direction away from the shanks and adapted 20 to be straightened before application of the staple, and said shanks adapted to assume a substantially parallel relationship when said arch is straightened.

MAX VOGEL. 25
